UNITED STATES PATENT OFFICE

KARL HAGENAUER, OF VIENNA, AUSTRIA

DESIGN FOR A HOLDER FOR A JAR OR SIMILAR ARTICLE

Application filed September 20, 1929. Serial No. 32,809. Term of patent 3½ years.

To all whom it may concern:

Be it known that I, KARL HAGENAUER, a citizen of Austria, and a resident of the city of Vienna, State of Austria, have invented a new, original, and ornamental Design for Holder for a Jar or Similar Article, of which the following is a specification, reference being had to the accompanying drawing, forming a part hereof in which—

Figure 1 is a plan view of the holder;

Figure 2 is a side elevation of the same, showing my new design, the dotted lines representing a jar;

Figure 3 is a side elevation of a part of the holder, the same being spread out flat to show the ornamentation; and

Figure 4 is a side elevation of the remaining side of the holder.

In Figure 2 of the drawing, one side of the holder is shown. In Figure 3 that portion of the design located between the dotted lines A and B represents a second side of the holder; that part of Figure 3 between the lines B and C represents a third side of the holder, and in Figure 4 that part of the design which appears between the dotted lines D and E represents the fourth side of the holder.

I claim:

The ornamental design for a holder for a jar or similar article, as shown and described.

KARL HAGENAUER.
